OVERSHOT GRAPPLE

George W. Bowen, Houston, Tex.

Application October 18, 1940, Serial No. 361,729

2 Claims. (Cl. 294—102)

This invention relates to a grapple and has particular relation to an overshot type of grapple specially designed for engaging with and pulling pump sucker rods and like objects from wells.

Pump sucker rods are made up of sections connected by large couplings. These couplings are composed of very hard material and the conventional type of grapple will not take hold of the coupling with a sufficiently secure grip to permit the removal of a stuck rod that has been broken off in the well.

It is an object of the present invention to provide a novel type of overshot grapple which will securely engage either the enlarged coupling of the rod, or the rod itself and which may be designed to simultaneously engage both the coupling and the rod above the coupling and which will securely grip the same to permit the sucker rod to be pulled.

It is another object of the invention to provide a grapple of the character described which embodies one or more tubular bodies, or bowls, each having a helical downwardly and inwardly tapering inside face with a helical gripping jaw mounted on each face and whose outer side conforms to the shape of the corresponding face and whose inner side is toothed to engage the rod or the coupling thereof, said jaw being unattached to, and floating freely in, its bowl.

It is a further object of the invention to provide an overshot grapple of the character above specified embodying means whereby the inside diameter of the jaw may be slightly expanded, upon appropriate manipulation of the tool whereby the tool may be released from the engaged object.

With the above and other objects in view the invention has particular relation to certain novel features of construction, arrangement of parts and use, examples of which are given in this specification and illustrated in the accompanying drawing, wherein:

Figure 1 shows a longitudinal, sectional view of a form of the tool adapted to simultaneously engage both the coupling and the rod itself.

Figure 2 shows a cross-sectional view taken on the line 2—2 of Figure 1.

Figure 3 shows a cross-sectional view taken on the line 3—3 of Figure 1.

Figure 4 shows a longitudinal, sectional view of an embodiment of the invention adapted to engage the rod only, and

Figure 5 shows a longitudinal, sectional view of a form of the tool adapted to engage the coupling only.

Referring now more particularly to the drawing wherein like numerals of reference designate the same parts in each of the figures, the numeral 1 designates a tubular connecting nipple whose upper end is attached to an operating string 2 which extends to the ground surface. The lower end of the nipple 1 has an inside bowl 3 whose inner wall is formed with a helical, downwardly and inwardly tapering, inside face 4 extending to the lower end thereof. On this face there is a helical gripping jaw 5 whose outer side tapers downwardly to conform to the shape of and to fit closely on the face 4 and whose inner side is toothed to effectively engage and grip the sucker rod 6 or other similar object.

In the form shown in Figure 4 there is a guide 7 screwed onto the lower end of the nipple 1 and whose lower end is flared as shown. This form of the grapple is specially designed for engaging 10 with a section of the rod should the rod become broken at a point distant from the coupling.

As is well known pump sucker rods are made up of sections whose connected ends are similar and are connected by means of couplings such as 15 8. The couplings are of somewhat greater diameter than that of the rod sections and are usually formed of very hard material so that the conventional type of overshot heretofore used will not take hold of them securely. The type of

20 grapple shown in Figure 1 as well as that shown in Figure 5 have been found to be very effective in taking hold of and securely gripping this sucker rod coupling. The form shown in Figure 5 has been adapted specially for engaging the

25 sucker rod coupling alone. It comprises the nipple 1a which, as is noted, may be formed solid. Screwed onto the lower end of this nipple there is the tubular sleeve-like bowl 9 which is provided

30 with a helical, downwardly and inwardly tapering, inside face 10 and on this face there is a helical gripping jaw 11 whose outer side tapers downwardly to conform to the shape of and to fit closely on the face 10 and whose inner side is toothed to effectively engage and grip the coupling 8.

Attached to the lower end of the bowl 9 there is a tubular guide 12 whose lower end is downwardly and outwardly flared so as to guide the tool over the coupling. 35

40 In case the sucker rod becomes broken off beneath the coupling the type of grapple shown in Figure 4 may be effectively employed but should it becomes broken off a short distance above the coupling the type of grapping tool 45 shown in Figure 1 may be employed and this

type may be assembled by combining the bowl 9, with the jaw 11 therein, with the nipple 1 as shown in Figure 4, with the jaw 5 therein, first having removed the guide 7 from said nipple 1 and substituting an inside guide 7a which is screwed into the upper end of the bowl 9 into abutting relation with the lower end of the nipple 1.

In each form the operating string 2 above referred to may consist of the upper portion of the sucker rod which is parted. The selected form of the grapple may be attached to the lower end of the upper section of the sucker rod and lowered over the upper end of the broken off section remaining in the well. If the sucker rod is broken off immediately beneath the coupling, the form shown in Figure 4 may be employed, but if broken off at or a short distance above the coupling the form shown in Figure 5 may be employed.

In some instances, however, the rod may have parted at such distance above the coupling that the form of grapple shown in Figure 1 may be employed wherein the lower jaw 11 will engage with the coupling 8 and the upper jaw 5 will engage with the rod 6 above the coupling and a very secure grip with the broken off section thus obtained.

As the grapple is lowered over the rod or coupling the jaw will frictionally engage the rod or coupling, as the case may be, and upon an upward pull the tapering face will co-act with the corresponding tapered jaw so as to contract the jaw and cause it to securely grip the object engaged by it.

The lower end of the bowl 3 is provided with an inside abutment 13 and the lower end of the bowl 9 is provided with an inside abutment 14. As shown these abutments consist of longitudinal, dove-tailed splines, or keys. These are positioned to engage against the corresponding lower ends of the respective jaws. In case it should become desirable to release the grapple from the sucker rod in the well the operating string may be turned to cause the abutment to engage the opposing lower end of the corresponding jaw and a further turning movement will cause an expansion of the jaw so that by a continued turning in the same direction and an upward pull on grapple it will readily release the stuck object.

The drawing and description are illustrative

merely and it is not intended to restrict the invention thereby except as defined by the appended claims.

What I claim is:

- 5 1. A sucker rod grapple comprising a tubular bowl which is threaded at both ends and has an inside downwardly and inwardly tapering helical face, a helical jaw on said face whose inner side is toothed to engage an object in the grapple and whose outer side conforms to the taper of, and rests upon, said face to cause contraction of the jaw into engagement with said object upon upward movement of the grapple, said jaw being independent of and unattached to the bowl, said 10 bowl having an axial inside dove-tailed slot at the end of the tapering face, a pin in the slot forming an abutment engageable against the end of the jaw whereby upon appropriate turning and upward movement of the grapple the jaw will be caused to expand to release said object, a guide threaded into the lower end of the bowl and contacting the pin, a tubular connecting nipple threaded into the upper end of the bowl.
- 15 2. A sucker rod grapple comprising a tubular connecting nipple forming an upper bowl, a lower bowl threaded to the nipple, each of said bowls having an inside downwardly and inwardly tapering, helical face, a helical jaw on each of said faces whose inner side is toothed to engage an object in the grapple and whose outer side conforms to the taper of, and rests upon, said faces to cause contraction of the jaw into engagement with said object upon upward movement of the grapple, the lower jaw being substantially twice 20 the diameter of the upper jaw, said jaws being independent of and unattached to the bowls, an inside guide threaded into the upper end of the lower bowl below and in abutting relation with the lower end of the nipple, each of said bowls 25 having an axial dove-tailed slot at the end of the tapering face, a pin in each slot forming an abutment engageable against the end of the respective jaw whereby upon appropriate turning and upward movement of the grapple the jaws will be caused to expand and release said object, the pin in the upper bowl slot being retained therein by the inside guide, a lower guide threaded into the lower end of the lower bowl and positioned to retain the pin in the lower 30 bowl slot.
